PACKER

Charles S. Crickmer, Dallas, Tex., assignor to
Merla Tool Company, Dallas, Tex., a firm

Application July 24, 1936, Serial No. 92,428

8 Claims. (CL 166—12)

This invention relates to new and useful improvements in packers.

One object of the invention is to provide an improved packer particularly adapted for use in 5 a well casing.

An important object of the invention is to provide an improved well packer having means at its upper end for controlling the flow of well fluid through said packer, said means being so 10 arranged as to positively prevent the flow therethrough when the packer is in a set position.

Another object of the invention is to provide an improved well packer having means for bypassing well fluid therethrough, with a double 15 seal for closing the flow therethrough, whereby all danger of leakage is eliminated.

A still further object of the invention is to provide an annular valve at the upper end of a well packer for controlling the flow of fluid 20 through the packer, and a sliding member arranged to further seal the valve opening, whereby when the packer is in a set position, a positive seal preventing fluid from flowing through the packer is had.

25 A further object of the invention is to provide an improved well packer which is constructed of a minimum number of parts and which may be readily lowered into a well casing and set at any position therein, and which will form a fluid tight seal; said packer also being arranged to be quickly removed from said casing.

A construction designed to carry out the invention will be hereinafter described, together with other features of the invention.

35 The invention will be more readily understood from a reading of the following specification and by reference to the accompanying drawings, in which an example of the invention is shown, and wherein:

40 Figure 1 is a view partly in elevation, and partly in section and showing the upper portion of a well packer, constructed in accordance with the invention, disposed within a well casing, the packing element being in its normal position.

45 Figure 2 is a view partly in elevation, and partly in section and is a continuation of the parts shown in Figure 1, and showing the lower end of the packer.

50 Figure 3 is a view similar to Figure 1 and showing the packing element in its distorted position.

Figure 4 is a continuation of Figure 3, showing the lower portion of the device.

55 Figure 5 is a horizontal, cross-sectional view taken on the line 5—5 of Figure 1.

Figure 6 is a horizontal, cross-sectional view taken on the line 6—6 of Figure 1,

Figure 7 is a horizontal, cross-sectional view taken on the line 7—7 of Figure 1, and

Figure 8 is a horizontal, cross-sectional view 5 taken on the line 8—8 of Figure 1.

In the drawings, the numeral 10 designates an elongate tubular mandrel which is provided with suitable screw threads 11 at its upper end. The lower end of the mandrel is provided with similar 10 threads 12 and radial guide wings 13 are preferably formed integral with the lower end of said mandrel, being located just above the threads 12. The upper end of the mandrel is threaded into an elongate coupling collar 14 which has the 15 upper end of its bore internally threaded at 15, whereby said collar may be connected to the tubing (not shown). The provision of the threads 12 at the lower end of the mandrel permits said mandrel to be readily connected at any point in 20 the well tubing.

The coupling collar 14 is enlarged at its lower end and this enlarged portion is provided with a depending annular skirt 16, as is clearly shown in Figure 1. The inner diameter or bore 17 of 25 said skirt is greater than the outer diameter of the mandrel 10, whereby an annular space 18 is formed between the skirt and mandrel. The extreme lower end of the skirt 16 is bevelled at 19 to form a seating surface. 30

An elongate sleeve 20 surrounds the mandrel 10 and has an inner diameter which is greater than the outer diameter of the mandrel 10, whereby an annular space or passage 21 is formed between the mandrel and sleeve. The extreme 35 upper end of the sleeve is formed with inwardly extending lugs or webs 22 which engage the surface of the mandrel and serve to axially align said mandrel with the sleeve. The lower end of the sleeve is externally screw threaded to receive 40 the upper end of a slip supporting cone 23, which cone is normally supported on a recovery ring 10' which is welded or otherwise secured to the mandrel. The upper end of the cone is provided with an annular recess 24 which receives the 45 lower ends of an elastic packing element 25, which element may be constructed of rubber, rubber compound or other similar material. The packing element is elongate and as is clearly shown in Figure 1, surrounds the sleeve 20. The 50 upper end of the packing element is engaged by a suitable flanged cap 26 and thus, it will be seen that the packing element 25 is confined on the sleeve 20 between the cone and the cap. The cap is formed with an internal annular shoulder 55

27 which is arranged to be engaged by an outwardly directed annular flange 28 which is formed at the extreme upper end of the sleeve 20. The engagement of the flange with the shoulder occurs when the packing element 25 is in its normal or unexpanded position as shown in Figure 1. The flange and shoulder serve to limit the movement of the sleeve 20 with relation to the packing element 25, as will be hereinafter explained.

10 The cap 26 is provided with a bore 29 which bore has a diameter equal to the bore 17 of the skirt 16. The upper end of the cap is provided with an annular bevel 30 which forms a valve seat, and this bevel is inclined at the same angle as the bevel 19 formed on the underside of the skirt 16.

15 The cone 23 which is threaded on the lower end of the sleeve 20 has an axial bore 23' through which the mandrel 10 extends. The upper end of this bore is enlarged at 31 whereby an internal shoulder 32 is formed within the cone. It is noted that the enlargement of the bore 31 is of such size that this enlarged portion of the bore forms a continuation of the vertical 20 annular space 21 which is provided between the mandrel 10 and the sleeve 20. Above the shoulder 32, the cone is provided with a plurality of radial ports or openings 33, whereby communication is established between the interior of the 25 well casing A and the vertical space 21. Therefore, it will be seen that when the skirt 16 is lifted so that its bevel 19 is not engaging the annular seat 30 of the cap 26, fluid may flow from the well casing, through the port 33, annular space 21, and then outwardly through the space between the cap 26 and thimble 16. With this arrangement it will be seen that the fluid may bypass the packing element 25 by passing through the body of the well packer.

20 For setting the device within the well casing A, a plurality of gripping slips 34 are slidable on the surface of the cone 23. Any desired number of slips may be provided and each slip is carried by a supporting member 35 which has its upper end engaged in a recess 34' formed in the rear face of the slip. This upper end of the supporting member 35 is pivotally secured to the slip by a pin 36. The supporting member extends downwardly from the slip and is pivoted 25 on a pin 37 which is located within a slot 38 formed in the upper end of an elongate sleeve 39 which sleeve is separate from the cone 23 and is slidable on the mandrel. From the pin 37, the member 35 is continued downwardly and is curved outwardly so as to engage the inner wall of the well casing A. The extreme lower end of the member 35 is confined within a slot 40 provided in an annular flange 41 at the lower end of the sleeve 39. The member 35 is preferably constructed of a section of flat spring metal, whereby the inherent resiliency or tension of the member will hold the curved portion in frictional contact with the well casing at all times. In this manner, it is possible to form the slip supporting 30 member of a single piece and the lower end of the slip supporting member is thus utilized as a friction spring.

35 For connecting the sleeve 39 with the mandrel 10, whereby said mandrel and sleeve will move simultaneously, said sleeve is provided with a J-slot 42 (Figure 2). A radial pin 43 extends outwardly from the mandrel 10 and is arranged to engage within the slot 42. The pin is engaged in the horizontal leg 42' of the J-slot, and the sleeve is in such position with relation to the cone

23, that the slips 34 are held in their lowermost position on said cone as shown in Figure 1. In this position, the slips are retracted from the wall of the well casing A.

In the operation of the device the well tubing 5 (not shown) or any other suitable lowering tool is connected to the collar 14. The cone 23, packing element 25 and cap 26 are, of course, supported on the recovery ring 10' which is provided on the mandrel 10. The slips are, of course, held in their retracted position by the sleeve connected thereto by the members 35 and the sleeve is, in turn, connected to the mandrel by the engagement of the radial pin 43 in the J-slot 42. Since the mandrel is supported from its upper end it will be obvious that the skirt 16 will be in the position shown in Figure 1, that is, separated from the annular seat 30 on the upper end of the cap 26. Thus, as the device is being lowered into the well, the well 20 fluid within the casing may enter the radial ports 23 in the cone, pass upwardly through the annular space 21 between the mandrel and the sleeve 20 and then outwardly between the thimble and the cap. In this way there is practically no 25 resistance offered by the well fluid as the device is lowered into the well casing A.

When the point at which it is desired to set the packer is reached, it is only necessary to rotate the mandrel in a counter-clockwise direction so that the pin 43 on the mandrel will ride out of the horizontal leg 42' of the J-slot 42 and into alignment with the vertical leg thereof. When this occurs, a continued lowering of the mandrel will cause the pin to ride downwardly 35 through the vertical leg of the J-slot. At this time the sleeve 39, as well as the slips 34 which are fastened thereto by means of the members 35 is held stationary by the friction springs formed by the lower end of said members 35. 40 Therefore, as the mandrel, and cone, packing element and cap carried thereby, move downwardly with relation to the sleeve 39 and slip 34, it will be obvious that the slip will be moved upwardly with relation to the cone 23. Continued 45 downward movement of the cone through the slips causes a radial expansion of said slips, whereby the slips are moved into engagement with the inner wall of the well casing A.

When the slips move into their gripping position (Figure 3) it will be obvious that further downward movement of the cone will be prevented. Similarly, further downward movement of the packing element 25 and cap 26 is also prevented, as is the downward movement of the 55 sleeve 20. Therefore, a continued downward movement of the mandrel 10 will cause the recovery ring 10' to move away from the lower end of the cone 23. At the same time the skirt 16 which is an integral part of the coupling collar 60 14 attached to the upper end of the mandrel, also moves downwardly so that the bevel 19 at the underside of said skirt moves into engagement with the annular bevel seat 30 of the cap 26. When this occurs the flow of fluid through the 65 packer is cut off.

Continued downward movement of the mandrel causes the cap 26 to be moved downwardly and since the cone 23 is being held stationary by the slips 34, the packing element 25 will be distorted 70 radially into engagement with the wall of the well casing. At the same time that the packing element is being expanded, the sleeve 20 which is secured to the cone 23 remains stationary and, therefore, the upper end of the sleeve 20 moves 75

into the bore 17 of the skirt 16. At this time the outer periphery of the annular flange 28 at the upper end of the sleeve engages the inner wall or bore of the skirt. By the time the packing element 25 is fully distorted into its proper packing position, the upper end of the sleeve 20 has moved a substantial distance within the skirt, as is clearly shown in Figure 3. When the parts have assumed this position the packer is in its set position and at this time it will be obvious that the engagement of the bevel 19 of the skirt 16 with the seat 30 of the cap 26 will close the fluid opening which permits by-passing of the fluid through the packer. It has been found that in using a bevelled seat as that shown at the upper end of the cap 26, that extraneous matter and abrasive material present in the oil, such as sand will accumulate on the seat 30. Therefore, when the skirt 16 moves downwardly to engage the seat such sand and other extraneous matter will prevent a positive closing of the fluid opening. This would permit a leakage of the fluid through the packer. The possibility of leakage past the seated valve is obviated in the device shown in the drawings by the movement of the upper end of the sleeve 20 into the skirt 16. It will be obvious by observing Figure 3 that should a leakage occur at the point where the bevel 19 engages the seat 30 then the fluid would be trapped around the upper end of the sleeve 20, because the fluid could not pass between the outer periphery of the external flange 29 on the sleeve, which flange is engaging the bore 17 of the skirt 16. Therefore, a double valve is provided at the upper end of the packer and positively prevents any leakage of fluid after the packer has been set.

Another feature of the sleeve 20 which moves upwardly within the skirt 16 is that when the valve is first being opened at the time that the packer is ready to be removed from the well, the high velocity created by the cracking of the valve is eliminated. When the mandrel 10 and collar 14 attached to its upper end are first raised in removing the packer from the well casing A, it is obvious that the cone still remains stationary. Therefore, the collar 14, skirt 16 and mandrel 10 begin an upward movement. At this time, the cap 26 remains stationary within the well casing because the packing element 25 after having been set for some time, adheres or sticks to the wall of the casing A. Therefore, upon initial upward movement of the collar 14 and mandrel 10, the bevelled lower end 19 of the skirt 16 will move upwardly away from the bevelled seat 30, whereby a small space is provided between the seat and the bevel 19. As soon as the skirt leaves said seat, the fluid above the packing element will tend to flow downwardly between the space thus formed above the seat. It is obvious that upon initial movement of the collar or raising of the seat this opening is comparatively small and, therefore, the velocity of the fluid flowing over the valve seat 30 is comparatively great. However, as the skirt 16 is raised from the seat 30, it will be seen that said skirt must travel a predetermined distance before said skirt moves above the upper end of the sleeve 20 which is engaging within the bore 17 of said skirt. Therefore, as the skirt first moves upwardly, the upper end of the sleeve 20 remains within the bore of said skirt and, therefore, the fluid cannot enter the annular space 21 formed between the sleeve 20 and the mandrel 10 and as the skirt 16 is being separated from the seat 30, the upper end of the sleeve

serves to cut off the flow of fluid from above the packing element 25. Therefore, until such time as the skirt has been raised to provide an increased opening, the sleeve 20 prevents a flow through the packer. By the time the skirt has been raised sufficiently to remove the upper end of the sleeve 20 from within said skirt, the opening between the skirt and the seat 30 is such that the fluid flowing therethrough will not be pinched, and thus the velocity of said fluid is not sufficient to cut out or otherwise damage the valve seat.

After the valve has been opened, a continued upward movement of the mandrel 10 will cause the recovery ring 10' to strike the lower end of the cone and move said cone upwardly from between the slips 34. When this occurs, the spring member 35 will, of course, immediately return the slips 34 to their original position at the lower end of the cone. In this manner the device may be readily removed from the well casing. It is noted that the sleeve 20 is an important part of the invention for it not only provides a double seal at the upper end of the device, whereby a leakage of fluid through the packer is prevented when said packer is in a set position, but it also prevents a velocity of fluid being built up upon removal of the packer from the well casing.

What I claim and desire to secure by Letters Patent, is:

1. A well packer including, a support having a fluid passage therethrough, a packing element mounted on said support, a valve seat above said element, a valve carried by the support and adapted to engage the seat being normally in an open position to permit flow of fluid through the packer, means for distorting the packing element into its packing position, means for closing the valve above said element to cut off the flow of fluid through the support when the packing element is set, and means confined by the packing element and movable with relation thereto for sealing the point of intersection of the valve and seat.

2. A well packer including, a support having a fluid passage therethrough, a packing element mounted on said support, a valve seat above said element, a valve carried by the support and adapted to engage the seat being normally in an open position to permit flow of fluid through the packer, means for distorting the packing element into its packing position, means for closing the valve above said element to cut off the flow of fluid through the support when the packing element is set, means for releasing the packing element from its set position to permit removal from the well, means for opening the valve above the element upon initial upward movement of the support, and means adjacent the valve seat and movable with relation to said seat for preventing a flow through the valve until said valve has opened a predetermined distance.

3. A well packer including, a support having a fluid passage therethrough, a packing element mounted on said support, a valve seat above said element, a valve carried by the support and adapted to engage the seat being normally in an open position to permit flow of fluid through the packer, means for distorting the packing element into its packing position, means for closing the valve above said element to cut off the flow of fluid through the support when the packing element is set, means for sealing the point of intersection of the valve and seat, means for releasing the packing element from its set posi-

tion to permit removal from the well, means for opening the valve above the element upon initial upward movement of the support, and means adjacent the valve seat and movable with relation 5 to said seat for preventing a flow through the valve until said valve has opened a predetermined distance.

4. A well packer adapted to be lowered into a well casing including, a supporting mandrel, a 10 sleeve surrounding the support and having a greater diameter than the mandrel whereby an annular fluid passage is formed therebetween, a packing element surrounding the sleeve and slideable with relation thereto, means on the mandrel 15 for supporting the element, a cap engaging the upper end of the packing element and also slideable with relation to the sleeve, a valve seat at the upper end of the cap, an annular valve carried by the mandrel for engaging the valve seat 20 to close the annular flow space formed between the support and sleeve, and means for preventing downward movement of the packing element to permit the weight of the support to be placed on the element through the annular valve engaging 25 the cap, whereby said element is distorted, the downward movement of the support, cap and valve due to the distortion of packing element causing said cap and valve to move downwardly around the upper end of the sleeve, whereby the sleeve overlaps the intersection of the valve and seat to provide a further seal against leakage, the movement of the cap and valve with relation to the sleeve being such that upon upward movement of the support, the valve is raised from its seat a comparatively large distance before said valve moves above the sleeve, whereby the damage to 15 the valve or seat due to fluid velocity is obviated.

5. A well packer adapted to be lowered into a well casing including, a support, a sleeve surrounding the support and having a greater diameter than the support whereby an annular fluid 30 passage is formed therebetween, a packing element surrounding the sleeve and slideable with relation thereto, means on the support for supporting the element, a cap engaging the upper 35 end of the packing element and also slideable with relation to the sleeve, a valve seat at the upper end of the cap, an annular valve carried by the support for engaging the valve seat to close the annular flow space formed between the support 40 and sleeve, and means for preventing down-

ward movement of the packing element to permit the weight of the support to be placed on the element through the annular valve engaging the cap, whereby said element is distorted, the downward movement of the support, cap and valve due to the distortion of packing element causing said cap and valve to move downwardly around the upper end of the sleeve, whereby the sleeve overlaps the intersection of the valve and seat to provide a further seal against leakage, the movement of the cap and valve with relation to the sleeve being such that upon upward movement of the support, the valve is raised from its seat a comparatively large distance before said valve moves above the sleeve, whereby the damage to 15 the valve or seat due to fluid velocity is obviated.

6. A well packer including, a support, a packing element mounted on said support, means for bypassing fluid through the support around said packing element, means for distorting the packing element into packing position, means for closing the by-pass when said packing element is set, and auxiliary means for sealing the by-pass opening when the same is in a closed position.

7. A well packer including, a support, a packing element mounted on said support, means for bypassing fluid through the support around said packing element, means for distorting the packing element into packing position, a valve above the packing element for closing the by-pass when 30 said packing element is set, and additional means adjacent the valve for preventing leakage thereby when the same is in a closed position.

8. A well packer including, a sleeve having a by-pass therethrough, a deformable packing 35 mounted on said sleeve, a collar having a seat slidably mounted on said sleeve and resting upon said packing, a closure having a bore and a face for engaging the seat of the collar to depress said collar and expand the packing, whereby the sleeve telescopes the bore of the closure, and a flange on the sleeve engaged by the collar to limit the return movement of said collar when the closure is removed.

CHARLES S. CRICKMER. 45
